GLOVE

Bert Kennedy, Johnstown, N. Y.

Application February 13, 1937, Serial No. 125,630

2 Claims. (Cl. 24—266)

This invention relates to gloves.

An object of the invention is the provision of a glove having a lace in combination with means in the body of the glove for tightening the lace, and for retaining the said lace in position, whereby the glove is retained upon the hand of the wearer.

Another object of the invention is the provision of a glove in which the body portion is equipped with a common opening for the ends of a lace and a pair of spaced openings, so that when the ends of the lace are passed through the openings said ends will be crossed and in frictional contact with each other while the walls of the openings will frictionally engage the ends of the lace for retaining said ends in position when the lace has been drawn up tight for snugly retaining the glove around the wrist of the wearer.

A further object of the invention is the provision of a glove having a lace encircling the wrist portion thereof with the ends of the lace passed through openings of smaller area than the cross sectional area of the lace for frictionally retaining the ends of the lace in position in connection with the pressures of the wrist against those portions of the lace which are disposed at the inside of the wrist portion.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in perspective of a glove constructed according to the principles of my invention.

Figure 2 is a fragmentary plan view of the glove showing the openings for the reception of the end portions of the lace.

Figure 3 is a view in perspective of the inside of the wrist portion of the glove showing the end portion of the lace in position.

Figure 4 is a transverse section taken along the line 4—4 of Figure 1.

Referring more particularly to the drawing, 10 designates a glove which may be made of leather or any suitable fabric and has a hand portion 11 and a wrist portion 12.

A piece of material 13 which may be of the same material, and from which the gloves have been manufactured, is secured at 14 in any ap-

proved manner, to the inner face 15 of the wrist portion 12. This reinforcement is substantially triangular in shape.

The outer face of the wrist portion is provided with an opening 20 which may be termed a common opening, for end portions 21 and 22 of a lace 23. The outer face of the wrist portion is also provided with spaced apart openings 24 and 25.

The reinforcement 13 is likewise provided with an opening 26 which is adapted to align with the opening 20 so that the openings 20 and 26 form substantially a common opening for the ends of the lace 23. The reinforcement is also provided with an opening 27 which aligns with the opening 24 in the wrist portion 12. Another opening 28 in the reinforcement which is spaced from the opening 27 aligns with the opening 25 in the wrist portion 12.

The end portions 21 and 22 of the lace 23 are equipped with any suitable ornament, as shown at 30, and these ornaments are of sufficient size 20 to prevent the free ends from accidentally being displaced from the openings in the wrist portion. It also serves as finger-pieces for drawing the free ends of the lace in position for causing 25 the wrist portion 12 to snugly fit the wrist of the wearer.

After the glove has been placed upon the hand of the wearer and after the end portions 21 and 22 of the laces have been loosened or moved outwardly from the openings 20 and 25 the lace 30 may be drawn up to maintain the proper pressure on the wrist without inconvenience to the wearer. This is accomplished by drawing on the finger-pieces 30 outwardly from the wrist portion, and 35 since the openings 20, 24 and 25 are restricted as compared to the cross sectional area of the lace the end portions 21 and 22 of said lace will be frictionally held by the walls of the opening and prevent slippage of said free ends.

It will also be noted that the free ends 21 and 22 of the lace cross each other at the common opening 20, and that the portions 31 and 32 of the lace which are located at the interior of the glove will be in engagement with the wrist 45 of the wearer so that the end portions of the laces are engaged in a number of points which will prevent slippage of the free ends.

Furthermore, if the laces have been drawn up too taut upon the wrist of the wearer, a movement of the wrist will tend to release these end portions sufficiently to allow free circulation.

Furthermore, the automatic locking of the end portions of the lace when they are drawn in position, will compensate for various thicknesses of 55

wrists of persons so that the wrist portion may comfortably fit the wrist without undue pressure.

I claim:

- 5 1. In a glove having a wrist portion, means for securing the glove to the wrist of the wearer and comprising a lace circumscribing the glove, the wrist portion of the glove having a common opening, a pair of spaced openings for the free end portions of the lace, one free end of the lace being threaded through the common opening and one of the pair of openings, the other free end of the lace being threaded through the other opening of the pair and the common opening with the ends of the lace crossing each other at the common opening, the ends of the lace where they cross exerting a binding action on each other, the area of the openings being less than the cross sectional area of the lace so that the walls of said openings will frictionally grip the lace and pre-
- 10
- 15

vent slippage, the ends of the lace extending in opposite directions to each other.

2. In a glove having a wrist portion, means for securing the glove to the wrist of the wearer and comprising a lace circumscribing the glove, a reinforcement secured to the inner face of the wrist portion, said wrist portion having a common opening and a pair of spaced openings through the reinforcement, one end of the lace being threaded through the common opening and one of the spaced openings, the other end of the lace being threaded through the other spaced opening and the common opening with the end portions of the lace crossing each other at the common opening and frictionally gripped by the walls of said openings to prevent slippage of the ends of the lace, the ends of the lace where they cross exerting a binding action upon each other.

BERT KENNEDY.
